United States Patent Office

Des. 231,344

Patented Apr. 16, 1974

231,344

TRAVEL TRAILER

Hobart G. Miller, Glenview, Ill., and James F. Mariol,
Cincinnati, Ohio, assignors to Apeco Corporation,
Evanston, Ill.

Filed Aug. 24, 1972, Ser. No. 283,368

Term of patent 14 years

Int. Cl. D12—10

U.S. Cl. D12—103

FIG. 1 is a right front perspective view of a travel trailer showing our new design;

FIG. 2 is a left, front perspective view thereof;

FIG. 3 is a rear fragmentary perspective view thereof; and

FIG. 4 is a top plan view thereof.

We claim:

The ornamental design for a travel trailer, as shown.
